(57) **CLAIM**

I claim the ornamental design for the child carrier, as shown and described.

DESCRIPTION

FIG. 1 is a front-elevational view of the child carrier, embodying my new design;

FIG. 2 is a rear-elevational view of the child carrier;

FIG. 3 is a left side-elevational view of the child carrier;

FIG. 4 is a right side-elevational view of the child carrier;

FIG. 5 is a top view of the child carrier; and,

FIG. 6 is a bottom view of the child carrier.

The broken lines shown on the surface of the article throughout the views are understood to represent stitching.
